UNITED STATES PATENT OFFICE.

HAROLD O. BIGNEY, OF ATTLEBORO, MASSACHUSETTS, ASSIGNOR TO SIDNEY O. BIGNEY, OF ATTLEBORO, MASSACHUSETTS.

DESIGN FOR A BRUSH-BACK AND MIRROR.

40,989.

Specification for Design.

Patented Nov. 15, 1910.

Application filed September 8, 1910. Serial No. 581,102. Term of patent 7 years.

To all whom it may concern:

Be it known that I, HAROLD O. BIGNEY, a citizen of the United States, residing at Attleboro, in the county of Bristol and State of Massachusetts, have invented a certain new, original, and ornamental Design for a Brush-Back and Mirror, of which the following is a specification.

In the accompanying drawings which form a part of this specification, the figure is a plan view of a brush back and mirror embodying my design.

I claim:—

The ornamental design for a brush back and mirror, as shown.

HAROLD O. BIGNEY.
